UNITED STATES PATENT OFFICE.

MARTIN J. CLAUSEN, OF SEATTLE, WASHINGTON, ASSIGNOR OF ONE-HALF TO HANS PEDERSON, OF KING COUNTY, WASHINGTON.

VEHICLE-SIGNAL DEVICE.

1,298,894.

Specification of Letters Patent. Patented Apr. 1, 1919.

Application filed April 23, 1918. Serial No. 230,212.

To all whom it may concern:

Be it known that I, MARTIN J. CLAUSEN, citizen of the United States, residing at Seattle, in the county of King and State of Washington, have invented certain new and useful Improvements in Vehicle-Signal Devices, of which the following is a specification.

This invention relates to improvements in vehicle signal devices and has for its principal object to provide an improved and novel manually operated signal for indicating the direction in which the vehicle intends to turn, in a device of the class described to provide means for automatically lighting the interior of the device at a pre-determined time. Another object of my device is to provide spring means for frictionally holding the device in any position set. The desirability of some form of signaling device for indicating the direction in which the vehicle wishes to turn at a street intersection is very well understood. Applicant has devised a simple and novel manually operated means for giving the desired signal and one which will work equally well in either the day time or night as means for lighting the device is provided.

Other objects will appear as my invention is more fully explained in the following specification, illustrated in the accompanying drawings and pointed out in the appended claims.

In the drawings Figure 1 is a sectional elevation of applicant's device shown attached to a fragment of a vehicle. Fig. 2 is a plan view of applicant's device. Fig. 3 is an enlarged cross sectional elevation of applicant's device showing the automatic switch means.

Referring more particularly to the drawings numeral 1 indicates a fragment of the dash board of a vehicle upon the side of which applicant's device is mounted by means of a bracket 2. The device itself consists of a rectangular and tubular outer casing 3 within which an indicator box 4 is slidably mounted. As shown in the drawings the indicator box is in extended and operable position. Integral with the top and bottom faces of the box 4 are spring extension members 5 which pass back through the casing 3 and terminate in a handle 6 beyond the opposite end of the casing. The inherent

spring of the members 5 cause them to bear 55 against the inner faces of the top and bottom of the casing with the result that they hold the signal box frictionally in any pre-determined position. The limit stop 7 on one of the members 5 limits the outward 60 movement of the signal box with respect to the casing. The signal box may be withdrawn within the casing by grasping the handle 6 and drawing it to the right which telescopes the box within the casing. The 65 front and rear sides of signal box 4 are each provided with a transparent arrow 8 and a painted arrow 9 both of which point in the same direction. The transparent arrow is for night use while the painted arrow is for 70 day use. An illuminating light 10 is mounted within the signal box 4 intermediate the transparent arrow so that at night the arrow is illuminated. It will be understood that when the signal is in the position shown in 75 Fig. 1 it indicates that the vehicle intends turning to the left and because of the arrow showing on both sides of the device the intentions of the vehicle operator will be apparent to both those in front and behind the 80 vehicle. In order to obviate the necessity of keeping the lamp 10 burning when the device is not in use an automatic switch arrangement is provided. The automatic switch device includes a contact plate 11 85 mounted near the forward end on one side of the casing 5 and just flush with the inner face of the said casing, and a spring switch member 12 which is secured to the inner end of the signal box 4 and which is connected 90 electrically to the lamp 10 so that when the contact 11 and spring switch 12 are in coöperation a continuous circuit is formed to the lamp. One of the wires 13 for the lamp passes up through the outer end of one of 95 the members 5 and thence directly to the lamp while the other wire 14 passes on the outside of the casing 3 to the contact 11. It will be understood that when the signal box is withdrawn within the casing that the light 100 is no longer connected and is therefore not lighted and further it is lighted only when in the extended position.

While I have shown a particular form of embodiment of my invention, I am aware 105 that many minor changes therein will readily suggest themselves to others skilled in the art without departing from the spirit

and scope of the invention, and I therefore desire to avoid being limited to the exact form shown and described.

Having described my invention, what I claim as new and desire to protect by Letters Patent, is:—

A manually operable signal comprising a fixed horizontal casing open at both ends, a hollow signal casing mounted to slide within the fixed horizontal casing closed at its outer end, a pair of oppositely resilient arms extending from the inner end of the signal casing and engaging the inner walls of the fixed casing and projecting beyond the inner

end of said fixed casing, a handle connecting the resilient arms, a stop on one of the arms to limit the outward movement of the signal casing, the signal casing having a signal indicated on its outer surface, the tension of the resilient arms serving to hold the signal casing projected from the outer end of the fixed casing or retracted therein, when moved by the handle.

In testimony whereof I affix my signature in the presence of a witness.

MARTIN J. CLAUSEN.

Witness:

IVAN L. HYLAND
